METHOD OF AND APPARATUS FOR OPERATING ON SHOES

Bernhardt Jorgensen, Marblehead, Mass., assignor to United Shoe Machinery Corporation, Paterson, N. J., a corporation of New Jersey

Application October 12, 1937, Serial No. 168,596
Renewed July 20, 1938

32 Claims. (Cl. 12—14)

This invention relates to methods of and apparatus for operating on the toes of partially fabricated shoes to prepare them for lasting with cement as the medium for securing the overlaid margins of the uppers to the insoles.

According to certain practices in lasting some types of women's shoes, for example, that disclosed in United States Letters Patent No. 1,815,296, granted July 21, 1931, on application 10 of George Goddu, a shoe may be side-lasting with staples, after which the toe may be lasted with cement. To prepare the toe for such lasting the preferred practice is to cut off a strip of the unlasted margin of the inner layers of material including a lining and a toe-stiffener that would, if not severed, mask the margin of the toe end of the insole when the toe of the upper is lasted, and thus prevent the overwiped margin of the upper from being bonded directly to the insole 20 with cement. For the sake of brevity the term "box" is used herein to mean the same as toe-stiffener, and the term "lining" is intended to include an interposed layer of woven fabric, commonly termed "doubler", that usually lies between an upper and a box.

The advantages in severing a strip from the margin of the inner layers comprising the lining and the box are so generally appreciated that virtually all shoes to be toe-lasting with cement 30 are so prepared, even though, in many shoe-factories, toe-lasting operators are required to do the severing with a knife held in the hand while the shoes are jacked in toe-lasting machines.

The present invention provides not only an improved machine for performing the severing operation above described, but also improvements in methods of preparing and lasting shoes which have special advantages with respect to shoes 40 provided with thermoplastic boxes.

According to the method herein set forth, the invention provides for turning out the unlasted toe-margin of the upper to unmask the corresponding margin of the inner layers, heating a 45 narrow band of the box coextensive with the perimeter of the insole sufficiently to melt the thermoplastic impregnant therein, heating to a lesser degree the lasting margin of the upper and the corresponding margin of the insole, severing a strip from the unlasted margin of the inner layers while the heating operation is in progress, applying lasting cement such as latex to the heated margins of the upper and the insole, and lasting the toe, as by overwiping the upper, before the heated band of the box loses all its plas-

ticity through dissipation of the heat. Although it has long been the practice to heat thermoplastic boxes immediately prior to toe-lasting, it is novel to trim them while they are being heated. By performing these two operations simultaneously, time is saved and the trimming operation is facilitated, since a cutter will operate much more readily on a thermoplastic box that is hot and soft than one that is cold and hard.

Moreover, since the time devoted to heating 10 and trimming the inner layers is utilized also to heat the toe-margin of the upper and the corresponding margin of the insole, these margins, if coated immediately with latex cement, will accelerate a tacky condition of the latter with the result that if the toe is lasted before the plasticity 15 of the box is gone the cement will be in a satisfactory condition.

A trimming machine organized according to the present invention as herein illustrated comprises heated members organized to engage the inner layers and the insole of a shoe before, during and after the actual time in which the trimming mechanism performs its function of severing a strip from the margin of the inner layers, 20 and some of the heated members supply radiant heat to the outturned margin of the upper while heating the inner layers by conduction.

The illustrated trimming machine also embodies improved features of construction, operation and control designed to insure a certain predetermined relation between the plane of the insole and the line along which the cutter severs a strip from the margin of the inner layers of material.

For example, the work is located and maintained in a certain predetermined position by a jacking mechanism that also shifts the heated members to their operative positions, and this movement of the jacking mechanism is utilized 35 to initiate the operation of a power-driven cutting mechanism that severs a strip progressively 40 while the work remains stationary and in the embrace of the heated members.

Again, the cutting mechanism is organized to 45 sever a strip from the margin of the inner layers of material with a series of draw cuts that progress simultaneously along both sides of the toe from a common starting point at the middle of the toe toward the heel end of the shoe.

Referring to the drawings,

Fig. 1 is a left-side elevation, partly broken away, of a combined heating and trimming machine organized according to the present invention;

- Fig. 10 is a perspective view of another train of operating connections and includes a portion of the other heated work-engaging member shown in Fig. 11;
- 30 Fig. 11 is a top plan view of two cooperative work-engaging members both of which are heated and designed to clamp and brace the margin of materials from which a strip is to be severed; and
- 35 Fig. 12 is a sectional view of the toe portion of a shoe in process of being lasted after a strip has been severed from the inner layers including the lining and the toe-box.
- The illustrated heating and trimming machine is intended to be located adjacent to a toe-lasting machine and to be used by a toe-lasting operator to prepare the toes of partially fabricated shoes for the toe-lasting operation.
- 40 The shoes delivered to this operator will have been previously side-lasted, preferably with staples 15, as shown in Figs. 2 and 4. At this stage, the lasting margin at the toe-end of the upper 16 is usually pulled over and temporarily secured to the insole 17 by a single tack, not shown, which also extends through the corresponding margin of inner layers which usually include a lining, a toe-box, and a doubler. The description will proceed on the supposition that the toe-box is of the thermoplastic type and is
- 45 interposed between the lining and the doubler and is bonded to both of the latter by the thermoplastic substance with which it is impregnated. Accordingly, these three elements, namely, lining, toe-box, and doubler are represented
- 50 as one layer 18 in Fig. 12.
- When the operator is ready to prepare a shoe for toe-lasting in accordance with the present invention, he will first pull out the toe-tack to release the pulled-over margins of the upper 16 and the inner layers 18 and will then turn out the margin of the upper to unmask the corresponding margin of the inner layers. Still holding the shoe in his hands, he will present it bottom up to the under surface of an abutment provided by a member 19 (Figs. 4, 5, and 11) that remains at a constant level to be engaged by the insole 17 and to locate it at that level. As shown in Fig. 11, the configuration of the member 19 corresponds approximately to the configuration of the toe-end of the insole, and the perimeter of
- 55 this member is therefore adapted to act with a plowing effect to spread the projecting margin of the inner layers 18 by engagement with the inner surface of the lining. Although the member 19 has no movement up or down, it is mounted to have a short horizontal movement toward the toe-end of the shoe after the insole has been placed against it, but this member is initially retracted from a cooperative clamping member 20 to facilitate the insertion of the projecting margin of the inner layers between the members. In Fig. 5, the members 19 and 20 are represented as having been moved toward each other to locate and clamp the interposed margin of the inner layers 18, but it is to be understood that in their initial positions they are both retracted.
- 60 Having located the toe-end of the shoe as above described, and still supporting the shoe in his hands, the operator depresses a treadle 21 (Fig. 1) from the position represented in dotted lines 20 to that represented in solid lines. One result of depressing the treadle is to raise a jack-post 22 by which a toe-rest 23 (Fig. 5) is brought against the toe of the shoe to maintain the insole firmly against the member 19 throughout the period required to heat the parts of the shoe and to sever a strip from the projecting margins of the inner layers 18.
- 65 Another result of depressing the treadle is to shift the members 19 and 20 toward each other 30 so that they will clamp a narrow band of the projecting margin from which a strip is to be severed and to bend that margin to an erect position. Still another result of depressing the treadle is to initiate the operation of a power-driven cutting mechanism by which the strip will be severed while the aforesaid narrow band of the projecting margin is clamped and in the embrace of the members 19 and 20. The shoe remains stationary and firmly braced by the members 19 and 20 and by the toe-rest 23 while the heating operation and the severing operation are in progress, and when the severing operation has been completed, the operator will release the treadle 21, remove the shoe from the heating 45 and trimming machine, coat the inner surface of the lasting margin of the upper 16 and the corresponding margin of the insole 17 (both of which margins are now heated) with lasting cement such as latex, place the shoe immediately 50 in the toe-lasting machine and perform the toe-lasting operation before the thermoplastic toe-box included in the layers 18 has cooled sufficiently to lose its plasticity.
- 70 Referring to Fig. 5, the toe-rest 23 is affixed to the upper end of a tube 24 and the latter is arranged in the jack-post 23 which is also tubular. The tubes 22 and 24 are telescopically related and the latter is normally projected upwardly by a compression spring 25 that provides a cushioning effect to maintain the insole of the shoe against the member 19 with yielding force. A pin or key 26 driven tightly into the jack-post 22 projects into a vertical slot 27 in the tube 24 to prevent rotation of the toe-rest and to maintain the spring under initial compression. The lower end of the spring 25 is seated on a pin 28 carried by the jack-post. The jack-post is arranged to slide up and down in spaced bearings 29 in the main frame of the machine and is normally depressed by a compression spring 30. The lower end of this spring acts against a collar 31 affixed to the jack-post while the upper end is seated against the upper bearing 29.
- 75 The mechanism for operating the jack-post 75

comprises, in addition to the treadle 21, a bell-crank lever 32, a link 33, a bell-crank lever 34, and an anti-friction roll 35 carried by the jack-post. The treadle and the bell-crank lever 32 are a unit and are connected to the main frame of the machine by a fulcrum pin 36. The bell-crank lever 34 is mounted on a rock shaft 37 and affixed thereto, the rock shaft being journaled in the main frame. When the parts of this mechanism occupy their initial positions, the surface 38 of the lever 34 underlies the roll 35 and is therefore effective to raise the jack-post as the treadle 21 is depressed, but the radial projection of the lever 34 is preferably limited to enable the free end of the lever to run past the roll after raising the latter to a predetermined level. This provision for overthrow of the lever 34 guards against excessive upward movement of the jack-post and the parts carried thereby and also guards against excessive stresses of those parts irrespective of the force with which the treadle is depressed. A concentric surface 39 formed on the lever 34 is arranged to bear against the roll 35 during the overthrow movement of the lever and thereby maintain the jack-post at its highest position.

The range of overthrow also provides for operation of a latch 40 by which the treadle may be maintained in its depressed position without requiring continuous effort on the part of the operator. The latch is carried by the treadle and is connected thereto by a pivot-pin 41. The upper end of the latch is provided with a notch and is adapted to abut the rock shaft 37. A tension spring 42 connecting the treadle and the latch swings the latch into its operative position when the treadle has been depressed as far as it should go. A pad 43 formed on the latch is arranged adjacent to the tread-plate of the treadle and may be depressed by the toe of the operator's foot to retract the latch while the heel of the same foot bears on the tread-plate of the treadle to control the upward movement of the latter.

As before stated, one result of raising the jack-post 22 is to move the member 19 horizontally toward the toe-end of the insole. For this purpose, the member 19 is carried by a horizontal bar 44 to which it is affixed in underslung relation by screws 45. The bar 44 has tongue-and-groove connection (see Fig. 2) with a supporting and guiding member 46 forming a part of the machine frame. The train of connections for communicating movement from the jack-post 22 to the bar 44 comprises a bell-crank lever 47, a pair of similar pivoted links 48 (Fig. 9), a pin 49 extending through both links, and an arm 50 affixed by a set screw 51 to a carrier 52 mounted on the jack-post. The bell-crank lever 47 is mounted on a stationary fulcrum pin 53 supported by a pair of hangers 54 formed on the guide member 46. A ball-and-socket connection 55 communicates motion from the bell-crank lever to the bar 44. The two links 48 suspended from spaced arms of the bell-crank lever 47 are alike in effect and construction, and they are spaced apart to receive between them the outer ends of the arm 50. The pin 49 is carried up and down without lost motion by this arm through which it extends, both ends of the pin 49 projecting therefrom and extending through vertical slots 56 in the links 48. These slots afford a range of lost motion between the pin 49 and the links 48, since the range of travel of the jack-post is more than enough to effect the desired length of travel of the member 19. The links are

provided with screws 57 arranged to be engaged by the pin 49 when the latter is descending. These screws are therefore instrumental in retracting the member 19 toward the heel-end of the shoe as the parts are returning to their initial positions, and the screws may be adjusted to regulate the extent of such retractive movement. In practice, a horizontal movement of about three-quarters of an inch of the member 19 is usually sufficient.

The member 20 (Fig. 11) that cooperates with the member 19 to locate the margin of the inner layers 18 and to clamp and brace a narrow band of that margin is not only moved toward and from the member 19 but it also partakes of the up-and-down movements of the jack-post 22. For this purpose, the rear end of the member 20 is pivotally connected by a pin 58 to the upper end of a bell-crank lever 59 (see Fig. 10). The fulcrum member of the bell-crank lever is the pin 49, a portion of the arm 59 being cut out to provide a space to receive this bell-crank lever. A link 60 suspended from the lever 59 extends loosely through a hole in a stationary arm 61 affixed to the frame of the machine as by screws 62 that secure it to the upper bearing 29. The lower portion of the link 60 is provided with a screw-thread and nuts 63 above and below the arm 61. These nuts afford a variable range of lost motion between the link and the arm and are also effective to oscillate the lever 59 in consequence of moving the jack-post up and down. When the parts are in their initial positions, the clamping member 20 is not only retracted to the rear but it also stands at a level about two inches below that of the member 19, but as the arm 59 rises with the jack-post, it elevates the lever 59 and the member 20, and when corresponding upward movement of the link 60 is arrested by the arm 61 and the nut below it, the resultant effect of further upward movement of the arm 59 is to oscillate the lever 59 in a direction to shift the member 20 toward the member 19. This movement of the member 20 occurs simultaneously with the movement of the member 19 in the opposite direction and results in clamping the upstanding margin of the inner layers 18 as shown in Fig. 5.

As shown in Fig. 11, the member 20 is a plate formed to provide a U-shaped recess or clamping surface 64 which is a counterpart of the perimeter 65 of the member 19, and when these members, once accurately adjusted, are brought to their operative positions, as shown in Fig. 5, they erect the projecting margin of the inner layers 18 and maintain it in a certain shape and location while a strip is being severed therefrom. Both the members 19 and 20 are heated by means herein-after described.

The carrier 52, by which the arm 50 is carried up and down, serves also to carry an electrically heated assemblage embodying certain features of improved construction hereinafter described. A portion of the carrier 52 is in the form of a sleeve and surrounds the jack-post 22. A collar 66 secured to the jack-post by a set-screw 67 supports the carrier 52 and provides for vertical adjustment thereof relative to the jack-post.

The members 19 and 20 and other parts to be described receive heat from a pair of metal blocks 68 (Figs. 1, 4, and 5) that undlie the member 20 and almost touch it. Much of the heat in these blocks passes by radiation to the member 20 and to the bar 44 which conducts a considerable amount to the member 19. The blocks 68 are

provided with sockets and these sockets contain electric heating units 69. As shown in Fig. 4, the blocks are arranged side by side, one at the right and the other at the left of a vertical plane coincident with the longitudinal median plane of the forepart of a shoe. Each block is also provided with a series of kerfs 70 arranged fan-wise and containing individually movable heat-conducting members 71, one in each kerf. The members 71 are all alike and one of them is shown individually in Fig. 6. A deep recess 72 is formed in each member 71 to receive the outturned margin of the upper 16 of a shoe and the top of this recess is bounded by an overhanging finger, 15 the tip 73 of which is arranged to abut the margin of the inner layers 18 in the plane of the insole 17, as shown in Fig. 5. The upper edges of these overhanging fingers provide support for the work-engaging margin of the member 20 which rests 20 thereon and is heated to a high temperature by reason of its engagement with the fingers. The kerfs 70 extend from top to bottom of the blocks 68 and the members 71 are supported in the kerfs by horizontal plates 74 secured to the bottoms of 25 the blocks and bridging the kerfs. Short stems 75 project downwardly from the lower edges of the members 71 and extend loosely through oversized holes in the plates 74. The members 71 are therefore free to rock on the supporting plates 30 within certain limits while these plates and the stems 75 maintain them in the kerfs. When the members 71 are all assembled in their respective kerfs, their work-engaging extremities 73 all but touch each other and provide a vertically continuous but conformable band of contact of the 35 heating structure with the work.

The members 71 are normally drawn toward a common center by a flexible metal cable 76 both ends of which are under constant stress of two 40 compression springs 77 (Fig. 4). The intermediate portion of the cable extends around both groups of members 71 and bears against their back edges 78. This portion of the cable extends through notches or grooves 79 that intersect the kerfs 70 (Fig. 5). The outlying portions of the cable 76 are led through eyes formed in upstanding brackets 80 and thence through the compression springs 77 and through collars 81 against which the springs exert their force to tension 45 the cable. The collars are secured to the cable 50 as by set-screws to provide for regulating the applied force of the springs. The brackets 80 are affixed respectively to two supporting rings 82 and 83 hereinafter described.

The entire heating assemblage is mounted on 55 and carried up and down by the carrier 52, but provision is made for adjusting the blocks 68 relatively to each other about a vertical axis virtually tangent to the meeting point of the two 60 groups of heat-conducting members 71 at the middle of the toe-end of the shoe. For this purpose, the blocks are mounted on and affixed respectively to the supporting rings 82 and 83 (Figs. 5 and 8). Two upright studs 84 extend through 65 each block 68 and are screwed into the corresponding ring to provide rigid connections. When the parts are assembled, the ring 82 is seated on an annular ledge formed on the carrier 52, and the ring 83 is superposed on the ring 82. Both 70 rings surround and bear on a cylindrical flange 85 formed on the carrier and are thereby maintained in concentric relation to the vertical axis above specified. The carrier 52 is constrained against all turning movement, and for this purpose it is provided with two horns 86 (Fig. 2)

that project, one to the right and the other to the left, beyond upright portions 87 of the main frame. The rear edges of these portions 87 are parallel with the axis of the jack-post 22 and they are engaged by the extremities of the horns 86 which may slide up and down on them.

The tension of the cable 76 normally draws the tips 73 of the heat-conducting members to positions from which they must be deflected by the toe portion of a shoe as the heating assemblage 10 rises with the jack-post 22. Consequently, the upward movement of the members 71, after the outturned margin of the upper 16 has been inserted into their recesses 72, causes an upwiping action of the tips 73 on the inner layers 18 where-by these layers are tensioned and conformed to the toe portion of the last incidentally to the 15 operation of raising the jack-post.

To provide for adjusting the blocks 68 and the fanned heat-conducting members 71 in accordance with the shapes of the toe-ends of shoes, the blocks are connected by a double-acting screw (Fig. 4) having a right-hand thread 88 and a left-hand thread 89. The threaded portions of the screw extend respectively through corresponding nuts 90 suspended from the blocks respectively and provided with cylindrical stems that bear in the blocks and provide swivel connections. The portion of the double-acting screw that lies between the nuts 90 is provided with a 30 circular flange 91 that projects into a kerf formed in an anchoring block 92 to prevent endwise movement of the screw and at the same time to permit rotation thereof. The block 92 is affixed to the arm 50 as shown in Fig. 5. One end of the 35 screw is provided with a hand-wheel 93 by which it may be rotated to adjust the blocks 68 simultaneously in opposite directions about the axis of the supporting rings 82 and 83.

When the outturned margin of the upper 16 of 40 a shoe projects into the recesses 72 (Fig. 6) of the heat-conducting members it receives radiant heat from these members and from the blocks 68, but to guard against excessive heat which might be detrimental to the upper, the cavity formed by 45 the recesses 72 and by the adjacent portions of the blocks 68 may be provided with a heat-baffle comprising an outer layer 94 of sheet asbestos and a reinforcing inner layer 95 of flexible sheet metal. The opposite ends of the sheet metal 95 50 may be affixed to the blocks 68 as shown in Fig. 4. This heat-baffle need not interfere with the movements of the members 71 relative to the blocks 68 but may be arranged to project into the recesses 72 below the outturned margin of the upper 55 to protect those portions of the upper that will be exposed to view in the finished shoe, and even if the lasting allowance of the upper touches the overhanging fingers of the members 71 the upper will not suffer any serious damage because these 60 points of contact will ultimately be concealed between the insole and the outsole of the shoe.

After the various heating, clamping, and conforming members are brought to their operative 65 positions, as shown in Figs. 1, 4, and 5, that portion of the upstanding margin of the inner layers 18 that projects above the members 19 and 20 is severed by mechanism now to be described. The cutter 100 for severing a strip from this margin is a thin blade, long and narrow and of about 70 the same dimensions as a common hack-saw blade, but instead of being provided with saw-teeth, it is provided with a knife-edge and is reciprocated lengthwise of that edge with short 75 rapid strokes to sever the strip with a series of

draw cuts. While the severing operation is in progress, the shoe remains stationary in a certain predetermined position established and maintained by the cooperative effects of the insole abutment 19, the toe-rest 23 and the clamping plate 20. The cutting edge of the blade 100 first engages the work at the middle of the toe, as shown in Figs. 1 and 5, and while the blade is being reciprocated lengthwise of its cutting edge, that is, crosswise of the shoe, it also moves toward the heel-end of the shoe in an arc that carries it upwardly, with the result that the severing of the strip begins midway between its ends and progresses simultaneously in opposite directions from the starting point and terminates at points near the tip-line of the shoe. As shown in Figs. 1 and 5, the upper surfaces of the members 19 and 20 are curved in accordance with the arc in which the cutting blade progresses while passing through the work. The members 19 and 20 barely clear the blade and therefore brace the work firmly against lateral deflection, inside and out.

As shown in Fig. 2, the blade 100 is affixed to the lower face of a pendulous carrier 101 of skeleton construction suspended from and fastened to a horizontal rock-shaft 102. The sliding bar 44 and a portion of its supporting structure 46 project through the space bounded by the carrier 101, and the sidewise dimension of this space is sufficient to provide for movement of the carrier from side to side without encountering interference. The rock-shaft 102 is arranged in bearings in the upright portions 87 of the main frame, and is operated not only to turn in its bearings but is also reciprocated lengthwise to carry the cutting blade lengthwise of its cutting edge. Rapid lengthwise reciprocation is imparted to the shaft by an electric motor 103 mounted on the supporting structure 46 at the rear of the machine. The driven shaft 104 of the motor lies at right angles to the shaft 102 (see Fig. 7) and the two shafts are connected by members comprising a wrist-pin 105, a wrist-pin block 106, a grooved block 107, and two collars 108 both fastened to the shaft 102 and flanking the block 107 which, although mounted on the shaft 102 is not fastened thereto except through the confining effect of the collars 108. The wrist-pin 105 is formed on a member 109 that is secured to the motor-shaft 104 by a set-screw 110. The shape of the member 109 and the distribution of its weight are designed to counterbalance the inertia of the mass that derives its reciprocatory movement from the motor-shaft, to the end that this mass may be operated at high-speed without serious vibration. As the block 106 is carried around in a circular path by the wrist-pin 105, it imparts only its components of horizontal movement to the shaft 102.

The electrical circuit by which the motor 103 is energized is initially open and is not closed until the jack-post 22 has been raised nearly, if not quite, to its highest position. For this purpose, the motor circuit is controlled by a switch 65 contained in a switch-box 111 (Fig. 2). This switch-box is mounted on a convenient portion of the main frame such as one of the upright portions 87. An operating arm or lever 112 (Fig. 3) for opening and closing the motor-circuit projects from the rear of the switch-box to be raised by a member 113 that is carried up and down by one of the horns 86 of the carrier 52. The arm or lever 112 is initially depressed by a tension spring 114 to open the motor-circuit, but, when 70 it is raised by the member 113, as shown in Fig. 3,

it closes the motor-circuit to initiate the operation of the cutting mechanism.

A torsion-spring 115 surrounding one end of the rock-shaft 102 tends normally to turn the rock-shaft in a direction to advance the cutting blade 100 from its initial position toward the heel-end of a shoe, but the blade is initially retracted out of range of the work and is not released for operation until the jack-post 22 has been raised by the treadle 21. One end of the spring 115 is anchored to a portion 87 of the main frame while the other end of the spring is operatively engaged with a collar 116 pinned or otherwise fastened to the shaft. The alternate compression and extension of the spring due to the lengthwise reciprocation of the shaft 102 is of no effect and may be disregarded. The opposite end of the shaft 102 is provided with a two-armed lever pinned or otherwise fastened thereto. One arm 117 of this lever is connected to some convenient member operated by the treadle 21 for the purpose of retracting the cutting blade to its initial position after it has severed a strip from the work. As shown in Fig. 1, the member for retracting the blade is an arm 118 affixed to the rock-shaft 37. Downward movement of the arm 118 is communicated to the arm 117 by a flexible cable 119, and the yoke or frame 101 is thereby retracted far enough to remove the cutting blade 100 from the work-receiving locality and to raise the end 120 of the two-armed lever above the level of a shoulder 121 formed on a latching member 122. This member is mounted on the stationary frame structure to which it is connected by a pivot stud 123. A tension spring 124 maintains the member 122 initially in its latching position in which the shoulder 121 underlies the portion 120, but when the latching member is retracted it releases the lever 117, 120, whereupon the torsion spring 115 (Fig. 2) swings the cutting blade into operation. This release occurs as the jack-post 22 rises, and is effected by a striker 125 that lifts an arm 126 of the latching member. This release of the cutting blade occurs virtually at the same instant when the electrical circuit for operating the motor 103 is closed by the controls shown in Fig. 3.

Although the longitudinal reciprocatory motion of the cutting blade is derived from the motor 103, the penetrating force and movement of the blade are derived from the torsion-spring 115. 50 This force is preferably not so great as to carry the blade through the work without the assistance derived from the lengthwise movement of the blade. Consequently, although the blade will be shifted quickly from its initial position to the position where it first encounters the material to be severed, its movement of penetration will be retarded by the material, and the retarding effect will be greatest at the beginning of the cutting operation because an interval of two or three seconds is necessary to heat the materials sufficiently to melt the thermoplastic substance with which the toe-box is impregnated. Once the thermoplastic substance is melted, the force of the spring 115 will accelerate the movement of penetration of the cutting blade, but whether the movement of penetration is slow or rapid, the longitudinal movements of the blade derived from the motor 103 will be executed at high speed.

The movement of the cutting blade toward the heel-end of the shoe is arrested by a shoulder 127 formed on the latching member 122 and arranged to be engaged by the portion 120 of the two-armed lever. This shoulder 127 is located at a 75

point that will permit the cutting edge of the blade to run out of the materials 18 at points near the tip-line of the shoe but will prevent the blade from moving so far as to encounter the horizontal bar 44 that overhangs it. The striker 125 that trips the cutting mechanism may be carried by any convenient part that partakes of the movements of the jackpost 22, but, as shown in Fig. 1, it is affixed to one of the blocks 68.

10 When the cutting blade has completed the operation of severing a strip, the operator will release the treadle 21 (Fig. 1) by depressing the pad 43 of the latching member 40 and will permit the treadle 21 to rise to its initial position. As the 15 jack-post descends to release the shoe, the cable 119 will return the cutting blade to its initial position where it will be automatically caught by the shoulder 121 of the latching member 122, the circuit for operating the motor 103 having, in the meantime, been opened by the spring 114 and the operating arm 112 (Fig. 3).

While a shoe is undergoing the heating and trimming operations of the machine hereinbefore described, the out-turned margin of the upper 16 is heated chiefly by radiant heat, the inner layers 18 are heated in some degree by radiant heat but in a greater degree by conduction from the members 19, 20, and 71, and the toe portion of the insole is moderately heated by conduction due to its engagement with the member 19. After removing a shoe from this machine, but before the heated parts of the shoe have lost any appreciable amount of their heat, the operator, to utilize the heat most advantageously according to the present invention, will apply a coating of lasting cement, such as latex, to the inner surface of the lasting margin of the upper 16 and to the corresponding margin of the insole. This may be done either by applying the cement with a brush or by discharging it under pressure from a nozzle of a spraying apparatus. The heat in the insole and in the margin of the upper will speed the evaporation of the moisture content of the cement and thereby accelerate the development of a tacky condition in the cement thus applied. If desired, the shoe may be placed in a toe-lasting machine (Fig. 12) prior to the operation of applying cement to the insole and the lasting margin of the upper, but in any event, the shoe will be placed 30 in a toe-lasting machine before the thermoplastic toe-box loses plasticity through dissipation of heat.

A toe-lasting machine of the type illustrated and described in United States Letters Patent No. 55 2,075,852, granted April 6, 1937, on an application in my name will be suitable to perform the toe-lasting operation in accordance with the method herein set forth. Such a machine is provided with a toe-rest 130 and with lasting wipers one 60 of which is indicated at 131. Having placed the shoe in a toe-lasting machine, the operator will cause the wipers 131 to wipe the lasting margin of the upper 16 over and against the insole 17, and the overwiped margin of the upper will fold or bend the remaining narrow margin of the inner layers 18 over and against the insole while the thermoplastic toe-box contained therein is still in a sufficiently plastic condition to be conformed 65 readily to the last and to the perimeter of the insole. In the meantime the heat retained in the insole and in the lasting margin of the upper will have rendered the lasting cement sufficiently tacky to insure a satisfactory bond of adhesion, 70 whereby the margin of the upper will be perma-

nently maintained in its final lasted position on the insole.

Having thus described the invention, what is claimed as new and desired by Letters Patent of the United States is:

1. That improvement in methods of preparing the toe ends of shoes for lasting, which consists in turning out the toe margin of the upper of a partially fabricated shoe from the corresponding margin of inner layers comprising a toe-box and a lining, and severing a strip from said margin of the inner layers with cuts that progress along both sides of the toe simultaneously from a common starting point at the middle of the toe toward the heel end of the shoe. 15

2. That improvement in methods of preparing the toe ends of shoes for lasting, which consists in turning out the toe margin of the upper of a partially fabricated shoe from the corresponding margin of inner layers comprising a toe-box and a lining, maintaining the inner layers against the top of the toe of the last with pressure applied thereto, and severing a strip from said margin of the inner layers with cuts that progress along both sides of the toe simultaneously from a common starting point at the middle of the toe toward the heel end of the shoe. 20

3. That improvement in methods of preparing the toe ends of shoes for lasting, which consists in turning out the toe margin of the upper of a partially fabricated shoe from the corresponding margin of inner layers comprising a toe-box and a lining, clamping a narrow band of the inner layers against the perimeter of the insole, and severing a strip from said margin of the inner layers outside but close to said clamped band. 30

4. That improvement in methods of preparing the toe ends of shoes for lasting which consists in turning out the toe margin of the upper away from the corresponding margin of inner layers, 40 heating said margin of inner layers to soften a thermoplastic substance therein, and severing a strip from the latter said margin while it is being heated.

5. That improvement in methods of preparing the toe ends of shoes for lasting, which consists in turning out the toe margin of the upper of a partially fabricated shoe from the corresponding margin of inner layers comprising a toe-box and a lining, heating and clamping a narrow band 50 of the inner layers adjacent to, and virtually parallel with the plane of the insole, and severing a strip from said margin of the inner layers outside said band while it is clamped and heated. 45

6. That improvement in methods of preparing the toe ends of shoes for lasting, which consists in turning out the toe margin of the upper of a partially fabricated shoe from the corresponding margin of inner layers comprising a toe-box and a lining, clamping a narrow band of the inner 60 layers adjacent to, and virtually parallel with the plane of the insole, and severing a strip from said margin of the inner layers with cuts that progress along both sides of the toe from a common starting point at the middle of the toe toward the heel end of the shoe. 55

7. That improvement in methods of preparing the toe ends of shoes for lasting, which consists in turning out the toe margin of the upper of a partially fabricated shoe from the corresponding margin of inner layers comprising a toe-box and a lining, clamping a narrow band of the inner layers adjacent to, and virtually parallel with the plane of the insole, and severing a strip from said margin of the inner layers with cuts that pro- 70

- gress simultaneously in opposite directions from a common starting point at the middle of the toe and run out gradually to the edge of said margin at points adjacent to the tip line.
- 5 8. That improvement in methods of preparing and lasting the toe ends of shoes, which consists in turning out the toe margin of the upper of a partially fabricated shoe from the corresponding margin of inner layers comprising a toe-box and a lining, clamping a narrow band of the inner layers adjacent to, and virtually parallel with the plane of the insole, heating said band, severing a strip from said margin of the inner layers outside said band while the latter is clamped and heated, and lasting the toe by wiping said margin of the upper over the newly trimmed edge of the inner layers and against the face of the insole while said band of the inner layers is heated.
- 10 9. That improvement in methods of preparing the toe ends of shoes which consists in turning out the toe margin of the upper of a partially fabricated shoe from the corresponding margin of inner layers comprising a toe-box and a lining, supplying dry heat to the outturned margin of the upper and the corresponding margin of the insole and simultaneously severing a strip from said margin of the inner layers along a line adjacent to the insole, applying an adhesive to said margins of the upper and the insole while they are heated, and lasting the toe by wiping said margin of the upper over the newly trimmed edge of the inner layers and against the adhesive margin of the insole.
- 15 10. That improvement in methods of preparing and lasting the toe ends of shoes, which consists in turning out the toe margin of the upper of a partially fabricated shoe from the corresponding margin of inner layers comprising a toe-box and a lining, pressing a narrow band of said margin of the inner layers against the perimeter of the insole and simultaneously supplying heat by conduction to said band and severing a strip from that margin adjacent to the insole but outside said band, and folding the newly trimmed edge of the inner layers over the edge of the insole while said narrow band is still heated by wiping said margin of the upper over and against the margin of the insole.
- 20 11. That improvement in methods of preparing and lasting the toe ends of shoes, which consists in turning out the toe margin of the upper of a partially fabricated shoe from the corresponding margin of inner layers comprising a toe-box and a lining, conforming a narrow band of the inner layers to the perimeter of the insole and simultaneously supplying heat by conduction to said band and to the margin of the insole and by radiation to said margin of the upper, severing a strip from said margin of the inner layers while heat is being supplied as aforesaid, applying an adhesive to the margin of the insole and to said margin of the upper while they are heated, and lasting the toe while said narrow band is still heated by wiping said margin of the upper over and upon the margin of the insole.
- 25 12. That improvement in methods of making shoes which consists in turning out the toe margin of the upper of a partially fabricated shoe, supplying dry heat to the insole and to said margin and simultaneously severing a strip from the corresponding margin of inner layers comprising a lining and a toe-box, applying thin films of adhesive cement to the insole and to said margin of the upper while it is heated, and last-
- ing the toe by wiping said margin of the upper over and into contact with the insole.
- 30 13. A trimming machine comprising means arranged to maintain an unfastened toe margin of the upper of a partially fabricated shoe away from the corresponding margin of inner layers, heating means arranged to heat said corresponding margin to soften a thermoplastic substance therein, and cutting mechanism the cutting element of which is arranged to sever a strip from said corresponding margin while the latter is in its operative relation to said heating means.
- 35 14. A trimming machine comprising clamping mechanism constructed and arranged to maintain the forepart of a partially fabricated shoe in a certain predetermined position, means arranged to maintain the toe margin of the upper outturned from the corresponding margin of inner layers comprising a lining and a toe-box, and power-operated cutting mechanism the cutting element of which is movable in a certain path to sever a strip from said corresponding margin with cuts that progress simultaneously in opposite directions from a common starting point at the middle of the toe and terminate at points near the tip line of the forepart.
- 40 15. A trimming machine as defined in claim 14 in which the cutting element is a thin blade and is operated with high-speed movement crosswise of the shoe and with slow-speed movement toward the heel end of the shoe.
- 45 16. A trimming machine as defined in claim 14 in which said clamping mechanism includes cooperative members formed and arranged to clamp a narrow band of said inner layers from which a strip is to be severed.
- 50 17. A trimming machine as defined in claim 14 and comprising also means controlled by operating movement of an element of said clamping mechanism to initiate the operation of said cutting mechanism.
- 55 18. A trimming machine comprising an abutment formed and arranged to be engaged by the bottom face of the toe portion of an insole and having a perimeter corresponding to that of such toe portion, means arranged to cooperate with said perimeter of the abutment to clamp a narrow band of a margin of unfastened shoe materials projecting beyond the bottom face of the insole of a partially fabricated shoe, means arranged to cooperate with the sole-engaging face of said abutment to clamp the toe of the shoe heightwise, and cutting mechanism the cutting element of which is movable in a certain predetermined path to sever a strip from said margin while said band and the toe of the shoe are both clamped as aforesaid.
- 60 19. A trimming machine comprising cooperative members formed and arranged to erect and clamp a band of a toe margin of unfastened shoe materials adjacent to but projecting beyond the bottom face of the insole of a partially fabricated shoe without masking an outer band of said margin, mechanism for imparting relative clamping movement to said members, a cutter arranged to sever said outer band substantially flush with said clamping members, and means arranged to operate said cutter.
- 65 20. A trimming machine comprising a carrier supported and guided to be movable angularly about an axis and independently movable lengthwise of said axis, a cutting blade carried thereby and having a cutting edge virtually parallel with said axis, mechanism arranged to reciprocate said carrier lengthwise of said axis to impart a draw-

- cutting motion to said blade, and means arranged to swing said carrier about said axis to give said blade a factor of penetration into work presented to said cutting edge.
- 5 21. A trimming machine comprising a bearing structure by which an axis is established, a carrier supported thereby, a cutting blade carried by said carrier and having a cutting edge virtually parallel with said axis, power-operated mechanism arranged to reciprocate said carrier lengthwise of said axis to operate said blade, and a spring arranged to swing said carrier about said axis in a direction to give said blade a factor of penetration into work presented to said cutting edge.
- 10 22. A trimming machine comprising a rock-shaft arranged in virtually horizontal bearings, a pendulous carrier affixed thereto, a cutting blade secured to said carrier and having a cutting edge virtually parallel with the axis of said shaft, an abutment arranged to be engaged by the upturned bottom of the forepart of a partially fabricated shoe presented toe-foremost to said cutting edge, power-driven mechanism arranged to reciprocate said rock-shaft lengthwise to operate said cutting
- 15 25 blade, a spring arranged to swing said carrier about said axis in a direction to give said cutting blade a factor of penetration into surplus material of the shoe projecting above the level of the insole, latching means by which said carrier is initially restrained against the force of said spring, and means for tripping said latching means to release said carrier.
- 20 23. A trimming machine comprising cooperative members formed and arranged to erect and clamp a band of a toe margin of unlasted shoe materials adjacent to but projecting beyond the bottom face of the insole of a partially fabricated shoe without masking an outer band of said margin, operating mechanism for imparting relative clamping movement to said members and to maintain them in a certain location at the termination of such relative movement, power-operated cutting means arranged to sever said outer band substantially flush with said clamping members, and means controlled by said operating mechanism to initiate the operation of said cutting means.
- 25 24. A trimming machine as defined in claim 23 comprising heating means by which one or more of said clamping members are heated sufficiently to soften a band of a thermoplastic toe-box included in the margin clamped thereby.
- 30 25. A trimming machine comprising an abutment formed and arranged to be engaged by the bottom face of the toe portion of a partially fabricated shoe having an unlasted margin of materials projecting beyond said face, wiping means movable to and from the plane of the insole in contact with the outer surface of said materials, mechanism arranged to operate said wiping means to draw said materials against the toe of a last, clamping mechanism comprising a member arranged to cooperate with said abutment to clamp a narrow band of said margin contiguous to the
- 35 40 45 50 55 60 65 perimeter of the insole, said member and said abutment having complementary U-shaped clamping surfaces to engage said margin, and cutting mechanism having a thin blade constrained to travel in a certain predetermined path to sever a strip from said margin.
- 6 26. A trimming machine as defined in claim 25 in which said wiping means comprises a series of individually yieldable work-engaging members and means by which they are normally maintained in positions to press a band of said materials against the perimeter of the insole.
- 11 27. A trimming machine as defined in claim 25 comprising also means arranged to heat said wiping means sufficiently to soften a band of a thermo-plastic toe-box included in the materials engaged thereby.
- 15 28. A trimming machine comprising a locating abutment having a surface maintained in a certain plane to be engaged by the bottom of the toe portion of the insole of a partially fabricated shoe, said abutment also having a convex perimeter to be engaged by a toe margin of unlasted shoe materials projecting beyond the bottom of the insole, a clamping member having an incurved surface providing a counterpart of said perimeter, operating mechanism arranged to impart relative movement to said abutment and said member to cause said perimeter and said incurved surface to clamp a band of said margin contiguous to the insole, and cutting mechanism the cutting element of which is constrained to travel in a certain predetermined path to sever a strip of said margin projecting beyond the band clamped as aforesaid.
- 20 29. A trimming machine as defined in claim 28 in which said cutting mechanism includes power-driven means for operating the cutting element, and controlling means operable by said operating mechanism to initiate the operation of said cutting mechanism.
